(57) **CLAIM**

The ornamental design for a lock as shown and described.

DESCRIPTION

FIG. 1 is a right front perspective view of the lock;

FIG. 2 is a left front perspective view of the lock;

FIG. 3 is a rear perspective view of the lock;

FIG. 4 is a front view of the lock;

FIG. 5 is a rear view of the lock;

FIG. 6 is a right side view of the lock;

FIG. 7 is a left side view of the lock;

FIG. 8 is a top view of the lock; and,

FIG. 9 is a bottom view of the lock.

The broken lines in the figures show portions of the lock that form no part of the claimed design.
